UNITED STATES PATENT OFFICE.

DORSEY A. LYON AND EDWIN R. COX, JR., OF HEROULT, CALIFORNIA.

ELECTRODE-HOLDER FOR ELECTRIC FURNACES.

1,068,148.

Specification of Letters Patent.

Patented July 22, 1913.

Application filed October 8, 1910. Serial No. 586,004.

To all whom it may concern:

Be it known that we, DORSEY A. LYON and EDWIN R. COX, JR., citizens of the United States, residing in Heroult, Shasta county, California, have invented certain Improvements in Electrode-Holders for Electric Furnaces, of which the following is a specification.

Our invention relates to means for supporting electrodes in that type of metallurgical furnace in which the heat of the electric current is caused to effect, or to aid in affecting, the reduction of the metal, one instance of such a furnace being that for which we filed application for Letters Patent on April 18, 1909, Serial No. 789,718.

The objects of our invention are to provide for the rigid support of the electrode, to prevent injury to the electrode holder due to the intense heat of the furnace, and to prevent the escape, around the electrode, of gases from the treating chamber of the furnace. These objects we attain in the manner hereinafter set forth, reference being had to the accompanying drawings, in which—

Figure 1 is a view, partly in elevation and partly in central longitudinal section on the line *a—a*, Fig. 2, of an electrode holder constructed in accordance with our invention; Fig. 2 is an end view, partly in section and looking at the holder in the direction of the arrow *x*, Fig. 1, but omitting the caps with which certain of the adjusting nuts are provided, and Fig. 3 is an end view of the holder looking in the direction of the arrow *y*, Fig. 1. Figs. 2 and 3 are on a smaller scale than Fig. 1.

The holder consists of an annular casing 1, with internal annular chamber 2, having an inlet 3 at the bottom and an outlet 4 at the top, so that water or other cooling agent may be caused to flow through the casing in order to prevent the destruction or rapid impairment of the same, and of the parts carried thereby, by the high degree of heat to which they are subjected.

Projecting externally from the casing 1 is a flange 5, having its periphery recessed to reduce its weight, said flange being stiffened and strengthened by means of ribs 6 extending from the back of the flange to the outer shell of the casing 1. The outer shell of the casing, at and near one end of the same, is externally threaded for the reception of a ring 7, the latter, in connection

with the bearing flange 5, constituting a clamp whereby the casing can be mounted upon a base, plate, ring, or other body 9 of insulating material, which is intended to be bolted to the casing of the furnace.

The bore of the casing 1 is tapered internally and to this bore is fitted the correspondingly tapered outer face of a split or sectional bushing 10, a bushing comprising three sections or segments being shown in the drawing, and said bushing being intended to confine the electrode, which is shown by dotted lines in Fig. 1, longitudinal inward movement of the sections of the bushing in the casing 1 serving to contract said sections of the bushing upon the electrode to firmly retain the same, and movement of the sections of the bushing in the opposite direction serving to release their hold upon the electrode in order to permit application, removal or longitudinal adjustment of the same.

When the electrode is properly clamped by the bushing, the intimate contact of the latter with both the casing and the electrode, and the extended area of such contact, insures perfect electrical connection between said casing and electrode.

The bushing has, at its outer end, a flange 11, comprising in the present instance three segments, one on each section of the bushing, this flange being free to move longitudinally in a chamber formed within an annular flange 12 projecting longitudinally from the outer face of the casing. The chamber also receives an annular follower 13, whereby a mass of packing 14, of asbestos or other heat-resisting material, can be confined between said follower and the flanged bushing, said packing bearing firmly upon the electrode, and preventing any escape, around said electrode, of gases from the working chamber of the furnace.

The follower 13 has a series of slotted lugs 100 for the reception of nuts 15, which have outer heads 16 and inner flanges 17, whereby they are longitudinally confined to the lugs but are free to turn therein, the nuts engaging stud bolts 19 which project longitudinally 105 from the casing 1.

Other stud bolts 20 project longitudinally from the flanges of the bushing 10 and pass through openings in the mass of packing and in the follower 13, these bolts 20 being 110 provided with nuts 21 which bear upon the outer face of the follower. When, therefore,

- 2
- the follower is backed off by proper manipulation of the nuts 15, it will pull the sections of the bushing with it and thereby loosen the hold of the same upon the electrode so as to permit of the removal, replacing or adjustment of the latter, the bushing being again tightened upon the electrode when the follower is again moved forward, or, if desired, the nuts 21 may be backed off before backing off the follower, and, after the pressure of the packing upon the electrode and upon the flanges of the bushing has been relieved, the bushing may be retracted by again tightening the nuts 21.
- Surrounding the casing 1 is a stiffening and strengthening web 22, terminating at the bottom in a projecting flange 23, to which may be connected the bus-bars or other conductors whereby the electric current is conveyed to the casing.
- The heads 16 of the nuts 15 are preferably circular and are provided with openings for the reception of a suitable implement whereby said nuts can be operated, and, being charged with the current, they are preferably provided with caps 24 of insulating material screwed upon the projecting portions of the bolts 19 in order to prevent injury to the attendants by contact with the nuts or bolts.
- We claim:
1. An electrode holder for furnaces, said holder comprising a casing with an internal adjustable clamp for the electrode, and an

external adjustable clamp for securing the 35 casing to its support.

2. An electrode holder for furnaces, said holder comprising a casing containing a clamp for the electrode, a compressible gas-checking ring surrounding the electrode and bearing upon the outer end of the clamp, and means for compressing said ring.

3. An electrode holder for furnaces, said holder comprising a casing having a chamber at one end, a sectional bushing having a flange movable within said chamber, a follower also movable in said chamber, and a mass of packing confined between said follower and the flange of the bushing and bearing upon the electrode so as to prevent the escape of gas around the latter.

4. An electrode holder for furnaces, said holder comprising a casing, a sectional bushing for confining the electrode therein, a follower, a mass of packing interposed between the follower and the bushing, means for adjusting the follower and means connected to the bushing and engaging said follower for effecting outward movement of the latter.

In testimony whereof, we have signed our names to this specification, in the presence of two subscribing witnesses.

DORSEY A. LYON.
EDWIN R. COX, Jr.
